UNITED STATES PATENT OFFICE.

CARTTER WEAVER, OF PITTSBURGH, PENNSYLVANIA.

ELASTIC ARMBAND.

1,070,642.

Specification of Letters Patent. Patented Aug. 19, 1913.

Application filed September 11, 1912. Serial No. 719,822.

To all whom it may concern:

Be it known that I, CARTTER WEAVER, a resident of Pittsburgh, in the county of Allegheny and State of Pennsylvania, have 5 invented a new and useful Improvement in Elastic Armbands, of which the following is a specification.

This invention relates to elastic bands or supports and particularly to the means for 10 adjusting the same to different sizes.

The object of the invention is to produce a simple, inexpensive and durable band adapted to be used as an arm band or hose supporter, which is perfectly flexible in all 15 directions, which may be considerably stretched or elongated without materially affecting its elasticity, and which is provided with means whereby its effective length may be varied to suit different sizes 20 of limbs.

The invention comprises the construction and arrangement of parts hereinafter described and claimed.

In the drawings Figure 1 is a perspective 25 view of an elastic arm band constructed according to my invention; Fig. 2 is a similar view of an elastic band arranged for use as a hose supporter; Fig. 3 is a plan view of the band shown in Fig. 1, with its ends separated; Fig. 4 is an enlarged longitudinal 30 sectional view on the line 4—4, Fig. 1; Fig. 5 is a perspective view of a spring clip; and Fig. 6 is a cross section on the line 6—6, Fig. 3, looking in the direction of the arrows.

The band shown in Fig. 1 is particularly 35 adapted for use as an arm band or sleeve supporter and is formed of a wire spiral 1 of suitable length and preferably formed of spring steel wire so as to be resilient, highly 40 elastic and durable. Preferably, the spiral is flattened, as shown in Fig. 6, to increase the width of the band, distribute the pressure on the arm and make the band compact and lie close to the arm. The end portions 45 or sections of the band telescope one into the other in order to permit the same to be adjusted to different sizes. For this reason, one end member or section 2 is of one size and the other end member or section 3 is 50 slightly larger in both cross sectional dimensions. The two portions 2 and 3 of the band may be formed of separate lengths of wire suitably connected together permanently at one end, as by soldering or intertwining of 55 the wires, or with a suitable catch, but preferably will be formed integral with

each other and of continuous wire, the coils of which gradually increase in size from the smaller portion 2 to the larger portion 3 thereof, as at 4. Although in Figs. 1, 2 and 60 3, for simplicity of illustration, only part of the wire coils have been shown in detail, and the rest conventional, it will of course be understood that the coils extend progressively and continuously all the way around 65 the band.

To secure the two free ends of the band in adjusted position, a spring clip 5 formed of thin metal plate bent upon itself has one end portion 6 inserted through the loops of the 70 large end portion 3 of the band to secure it thereto, the other portion 7 of the clip being bent at its end to form a tongue 8 which projects crosswise between the spirals of the small end of the band. The outer surface of 75 the portion 7 of the clip lies outside of the large or outer coil and may be embossed or impressed with any desired insignia or other advertising matter.

Preferably, the band is formed to be readily adjustable to any size of limb, so that it is unnecessary for the dealer to carry in stock a line of different sizes of bands. The small section 2 of the band is usually made considerably longer than the large section 3. In 80 practice the small section is say seven inches long and the large section five inches long, making twelve inches in all. This will fit the largest sized arm without unduly increasing the tension of the band when the same is 85 stretched. To adjust the band for a small arm, the outer portion 7 of the clip 5 is forcibly sprung away from the coils of the band. This presses the inner portion 6 tightly against the inside of the outer coils 3 90 and removes the tongue 8 from between the coils of the small section 2. The small section may then be telescoped into the large section within the clip 5 until the hand is reduced to a total length of seven inches, and 95 if this size is not small enough some of the short section 2 may be cut off in any manner.

Fig. 2 illustrates the device applied for 100 use as a sock or hose supporter. The elastic band itself is of the same construction and arrangement as that shown in Fig. 1 and comprises a wire spiral 1 having a large end section 3 and a small end section 2 which telescopes thereinto. 5 indicates the clip for 105 securing the two ends of the band to each other in adjusted position. On the opposite side of the band from the clip 5 it is pro-

vided with suitable means for the attachment of a hose supporter. In the forms shown in the drawings 6 comprises a substantially T-shaped metal member 10, the 5 two upper arms 11 of which are inserted between the coils of the wire into the space on the interior of the band. The member 10 has a depending arm 12 which projects out from between the wires of the coil and, has 10 secured to its lower end a strip of fabric 13, which may be either elastic or non-elastic as preferred, and to the lower end of which is attached a garment holding member 14 of any of the usual types of construction. The 15 arms 11 of the member 10 are made of such length that in use of the hose supporter they will not become detached therefrom with the elongation or stretching of the elastic band. They may be readily inserted, however, by 20 stretching the bands lengthwise and forcing them into place or, if preferred, one arm 11^a may be a separate member which is secured to the member 10 by riveting or otherwise, as at 15, after the arm 11 is inserted 25 into place. The flexible band, in the case of a hose supporter will preferably be made of greater length than in the case of an arm band but, if preferred, may be of the same length, in which case by removing the hose 30 supporting member 10 the band may be used as a sleeve supporter, if desired. The hose supporter is placed in position on the limb by stretching it and drawing it over the foot, the extreme flexibility of the wire coil 35 being such as to permit this.

The device is very simple and comprises but two parts. It is flexible in all directions, can be adjusted to increase or decrease its tension and is exceedingly durable. It is 40 also flat and therefore distributes the pressure, thereby obviating any danger of injury to the arm.

What I claim is:—

1. An elastic band adapted to be placed 45 around a limb comprising a flat hollow

structure of wire and having opposite end portions, and means for adjustably securing one of said end portions within the other to thereby vary the size of the band.

2. An elastic band adapted to be placed 50 around a limb, comprising a wire coil having end sections of different dimensions, one section being arranged to telescope into the other, and means for adjustably securing the telescoping end sections together, to thereby 55 vary the size of the band.

3. An elastic band adapted to surround a limb, comprising a wire coil having end sections of different dimensions, one section being arranged to telescope into the other, and 60 means for securing the telescoping end sections together, comprising a clip secured to one of said sections and having a transversely disposed tongue projecting between the coils of the other section.

4. An elastic band adapted to surround a limb, comprising a wire coil having end sections of different dimensions, one section being arranged to telescope into the other to thereby 70 vary the size of the band, and a clip secured to one end section of said coil and arranged to engage the wire of the other section.

5. An elastic band adapted to surround a limb, comprising a wire coil having end sections of different dimensions, one section being arranged to telescope into the other to thereby 75 vary the size of the band, and a clip secured to one end section of said coil and arranged to engage the wire of the other 80 section, said clip being formed of spring metal and adapted to be disengaged from said other section to enable the effective length of the band to be varied.

In testimony whereof, I have hereunto set 85 my hand.

CARTTER WEAVER.
